BUCKLE

Clarence M. Smith, Naugatuck, Conn., assignor to
 Parva Products Company, Chicago, Ill., a corporation of Delaware

Application October 27, 1939, Serial No. 301,545

8 Claims. (Cl. 24—194)

This invention relates to a buckle and has special reference to a slide buckle adapted to be mounted on a strap, band or the like, for securing articles together or for the support of garments or other objects.

More particularly, this invention relates to a buckle for association with a strap comprising a pair of frames disposed in a face-to-face relation for longitudinally slidable engagement therebetween, each having spaced side bars and spaced cross bars connecting the side bars for defining openings therethrough to receive the strap, and means for directing longitudinal movements of the frames, one cross bar of one of the frames having an inclined surface co-operating with one cross bar of the other of the frames to clamp the strap threaded therebetween in adjusted positions upon relative longitudinal movement of the frames in one direction, with means on one of the frames co-operating with the other of the frames upon relative longitudinal movement thereof in the other direction to obstruct the space between the inclined surface of the one frame and one end of the other frame whereby to facilitate the correct threading of the strap through the openings of the frames.

The device of the present invention may be adapted for use in various connections and, as a matter of fact, the construction may be employed with slight variations not departing from the spirit of this invention almost universally where detachable connections are desired. Hereafter and in the drawing the device will be described and shown in its association with the strap of a belt, although it is readily understood that the buckle may be employed with a strap for skates, books and the like, for attachment to lingerie, for encircling the leg as a hose supporter, for use as a suspender, or for detachable engagement with garments of various characters. It is, of course, to be understood that various other uses may be mentioned and that this invention is not to be limited to any single specific use.

The buckle contemplated herein is so constructed and arranged as to facilitate the correct threading of the strap through the openings of the frames. Each of the frames, which lie in a face-to-face relation for longitudinal slidable engagement, is provided with openings through which the strap is threaded. When the frames are in an unclamped position such that the strap may be threaded readily through the openings thereof, the end of one of the frames ordinarily presents a space between it and the other frame

which is sometimes mistaken for the opening through which the strap should be threaded since the end of one frame of the buckle, in an open position, ordinarily lies adjacent the strap-engaging cross bar of the other frame of the buckle. It is not, therefore, unusual to find that the user of the article incorrectly threads the strap through the wrong openings. The present invention has for one of its objects, therefore, to obstruct the space between the one end of the frame and the strap-engaging face of the other frame so that it is impossible to thread the strap therebetween and therefore a correct threading of the strap through the openings of the frames is facilitated.

One of the objects of this invention is to provide a buckle having relatively slidable frame members of the character indicated above in which the construction is relatively inexpensive to manufacture, is durable, and is simple in construction, in threading and in manipulation.

Another object of this invention is to provide a buckle having relatively slidable frame members of the type hereinabove described whereby the correct threading of the strap through the openings of the frames is facilitated.

Other objects and advantages of this invention will hereinafter be more particularly pointed out and, for a more complete understanding of the characteristic features of this invention, reference may now be had to the following description when taken together with the accompanying drawing, in which latter:

Figure 1 is a front view of a buckle incorporating the features of this invention as shown in its relation with a belt strap;

Figure 2 is an enlarged central sectional view of the buckle taken on the line 2—2 of Fig. 1, a portion of the strap being shown in dotted lines as being clamped in an adjusted position within the frames of the buckle;

Fig. 3 is a view similar to Fig. 2 showing the frames of the buckle in a changed position with the strap loosely threaded therethrough;

Fig. 4 is a sectional view taken on the line 4—4 of Fig. 1;

Fig. 5 is a perspective view of one of the frames of the buckle shown in Fig. 1; and

Fig. 6 is a perspective view of the other of the frames of the buckle shown in Fig. 1.

Referring now more particularly to the drawing, the construction therein shown as embodying the features of this invention comprises a pair of frame members 10 and 11, the frame member 10 being substantially rectangular in shape and

having spaced side bars 12 and 13 connected by spaced cross bars 14 and 15 to define a strap opening. The frame 11 is likewise substantially rectangular in shape and has spaced side bars 16 and 17 connected by spaced cross bars 18 and 19 forming a strap opening.

The side bars 12 and 13 of the frame 10 comprise opposed channels, ledges 20 and 21 (as shown more particularly in Fig. 4) extending in a direction inwardly toward each other from one edge of the side bars 12 and 13, respectively, and ledges 22 and 23 extending in a direction inwardly toward each other from the other edge of side bars 12 and 13, respectively. The opposed channels thus formed receive the side bars 16 and 17 of the frame 11 for directing relative longitudinal movements of the frames.

The cross bar 14 of the frame 10 is preferably inclined and has an extending portion bent back upon itself from the material of the opening of the frame to overlie the inclined portion and present an inclined strap-engaging face 24.

The cross bar 19 of the frame 11 is provided with an offset portion 25 which is preferably cut and deformed from the material of the frame to provide the strap opening therein, the offset portion being preferably of arcuate contour when viewed in cross-section for co-operation with the inclined surface 24 of the cross bar 14 to clamp a strap 26 in adjusted positions therebetween. The offset portion being rounded, while effectively preventing accidental movement of the strap from its clamped position, does not permanently mar the strap as pressure is applied between the strap-engaging surfaces. The side bars 16 and 17 are each provided with an extension 27 and 28, the extensions being preferably formed integrally with the side bars. The extensions 27 and 28 slidably engage in their longitudinal movement the opposed channels formed by the side bars 12 and 13 of the frame 10.

In order to prevent angular displacement of the frame 11 with respect to its normal longitudinal movement, the ledges 22 and 23 are provided with angularly extending flanges 29 and 30, respectively, the flanges 29 and 30 overlying the sides of the extensions 27 and 28 to form a guideway therefor. The frame 11 together with its extensions 27 and 28 lies wholly within the confines of the frame 10 even during the relative longitudinal movement thereof in both directions.

In the position shown in Fig. 2, the frame 11 is moved in one direction with respect to frame 10 to clamp the strap 26 between the strap-engaging offset portion 25 of the cross bar 19 and the strap-engaging inclined face 24 of the cross bar 14, the free end of the strap 26 being threaded through the opening in the frame 11 and between the offset portion 25 thereof and the inclined strap-engaging face 24 through the opening in the frame 10. The strap 26 is shown in a disengaged condition between the strap-engaging faces in Fig. 3, the frame 11 being moved in an opposite longitudinal direction to separate the offset strap-engaging portion 25 of the frame 11 with the inclined strap-engaging portion 24 of the cross bar 14.

In order to facilitate the correct threading of the strap through the openings of the frames 10 and 11, it is desirable that the space between the end of the cross bar 18 and the strap-engaging face 24 of the cross bar 14 be obstructed so that the strap cannot be threaded therebetween. The present invention contemplates as one form of

construction the provision of the opposed channels, the channels being of varying depth over the length thereof so that as the extension rides along one wall of the channel during relative longitudinal movement of the frames it will tilt the frame 11 with respect to the frame 10 so that the cross bar 18 will follow substantially the incline of the strap-engaging face 24. The space between the end of the frame 11 and the inclined strap-engaging face 24 will be obstructed by being smaller than the thickness of the strap during the positions of relative longitudinal movement of the frames so as to prevent the strap from being threaded therebetween.

Referring to Figs. 2 and 3, the opposed walls 20 and 22, and 21 and 23 of the respective channels forming the side bars 12 and 13, converge in the direction of the lengths thereof from the cross bar 14. The extensions 27 ad 28 ride along the walls 22 and 23 and in one direction of movement of the frames the extensions are depressed, as shown in Fig. 3, to tilt the frame 11 on the cross bar 19 so that the cross bar 18 is raised progressively as the extensions move in a direction outwardly from the cross bar 14.

When the strap is threaded through the opening in the frame 11, between the strap-engaging faces of the frames and out of the opening of the other frame 10 and tension is applied to the strap, the frames are moved from the condition shown in Fig. 3 to the position shown in Fig. 2, and the extensions 27 and 28 are permitted to rise and consequently tilt the frame so that the cross bar 18 may be lowered progressively into the position shown in Fig. 2. In no condition of use of the buckle can the strap be threaded through the frames 10 and 11, it being necessary that the strap pass through the openings of the frames in the correct position for clamping between the strap-engaging faces 24 and 25 thereof. The end of the frame 11 constituting the cross bar 18 is always in a position immediately adjacent to the strap-engaging face 24 so as to obstruct the space therebetween and to prevent the threading of the strap therethrough.

While but a single embodiment of this invention is herein shown and described, it is to be understood that various modifications thereof may be apparent to those skilled in the art without departing from the spirit and scope of this invention and, therefore, the same is only to be limited by the scope of the prior art and the appended claims.

I claim:

1. A slide buckle for association with a strap, comprising a pair of frames disposed in a face-to-face relation for longitudinally slidable engagement therebetween, said frames having spaced side bars and spaced cross bars connecting said side bars for defining openings therethrough to receive the strap, means for directing longitudinal movement of the frames, one cross bar of one of the frames having an inclined surface co-operating with one cross bar of the other of said frames to clamp the strap threaded therebetween in adjusted positions upon relative longitudinal movement of said frames in one direction, and means on one of said frames for tilting the other of said frames upon relative longitudinal movement of the frames in the other direction to obstruct the space between said inclined surface of the one frame and one end of the other frame whereby to facilitate the correct threading of the strap through the openings of said frames.

2. A slide buckle for association with a strap, comprising a pair of frames disposed in a face-to-face relation for longitudinally slidable engagement therebetween, said frames having spaced side bars and spaced cross bars connecting said side bars for defining openings there-through to receive the strap, means for directing longitudinal movement of the frames, one cross bar of one of the frames having an inclined sur-face co-operating with one cross bar of the other of said frames to clamp the strap threaded therebetween in adjusted positions upon relative longitudinal movement of said frames in one direction, and a projection fixed to and extending from one of said frames for engaging the other of said frames to effect a relative tilting between said frames upon relative longitudinal movement thereof in the other direction to obstruct the space between said inclined surface of the one frame and one end of the other frame whereby to facilitate the correct threading of the strap through the openings of said frames.
3. A slide buckle for association with a strap, comprising a pair of frames disposed in a face-to-face relation for longitudinally slidable engagement therebetween, said frames having spaced side bars and spaced cross bars connecting said side bars for defining openings there-through to receive the strap, means for directing longitudinal movement of the frames, one cross bar of one of the frames having an inclined surface co-operating with one cross bar of the other of said frames to clamp the strap threaded there-between in adjusted positions upon relative longitudinal movement of said frames in one direction, the side bars on one of said frames having tapered surfaces, and projections on the side bars of the other of said frames for engaging said tapered surfaces of the side bars to effect a relative tilting between said frames upon relative longitudinal movement thereof in the other direction to obstruct the space between said inclined surface of the one frame and one end of the other frame whereby to facilitate the correct threading of the strap through the openings of said frames.
4. A slide buckle for association with a strap, comprising a pair of frames disposed in a face-to-face relation for longitudinally slidable engagement therebetween, said frames having spaced side bars and spaced cross bars connecting said side bars for defining openings there-through to receive the strap, opposed channels formed on the side bars of one of said frames for receiving the side bars of the other of said frames for directing relative longitudinal movement of said frames, one cross bar of one of the frames having an inclined surface co-operating with one cross bar of the other of said frames to clamp the strap threaded therebetween in adjusted positions upon relative longitudinal movement of said frames in one direction, said channel side bars of one frame coacting with the sides of the other frame to effect a relative tilting of said frames upon relative longitudinal movement of the frames in the other direction to obstruct the space between said inclined surface of the one frame and one end of the other frame whereby to facilitate the correct threading of the strap through the openings of the frames.
5. A slide buckle for association with a strap, comprising a pair of frames disposed in a face-to-face relation for longitudinally slidable engagement therebetween, said frames having spaced side bars and spaced cross bars connect-ing said side bars for defining openings there-through to receive the strap, opposed channels formed on the side bars of one of said frames for receiving the side bars of the other of said frames for directing relative longitudinal movement of said frames, one cross bar of one of the frames having an inclined surface co-operating with one cross bar of the other of said frames to clamp the strap threaded therebetween in adjusted positions upon relative longitudinal movement of said frames in one direction, and extensions on the side bars of one of said frames coacting with said channel side bars of the other frame to effect a relative tilting of said frames upon relative longitudinal movement thereof in the other direction to obstruct the space between said inclined surface of the one frame and one end of the other frame whereby to facilitate the correct threading of the strap through the openings of the frames.

8. A slide buckle for association with a strap, comprising a pair of frames disposed in a face-to-face relation for longitudinally slidable engagement therebetween, said frames having spaced side bars and spaced cross bars connecting said side bars for defining openings there-through to receive the strap, opposed channels formed on the side bars of one of said frames for receiving the side bars of the other of said frames for directing relative longitudinal movement of said frames, one cross bar of one of the frames having an inclined surface co-operating with one cross bar of the other of said frames to clamp the strap threaded therebetween in adjusted positions upon relative longitudinal move-

ment of said frames in one direction, and extensions on the side bars of one of said frames tapering in the direction of their length, the opposed walls of said channel side bars of the other frame converging in the direction of the lengths thereof and coacting with said tapered extensions to effect a tilting of said frames upon relative longitudinal movement thereof in one direction to obstruct the space between said inclined surface of the one frame and one end of the other frame whereby to facilitate the correct threading of the strap through the openings of the frames. 5 10 15

CLARENCE M. SMITH. 15
